(57) **CLAIM**

The ornamental design for a device support for a power and data center, as shown and described.

DESCRIPTION

FIG. 1 is a front perspective view of a device support for a power and data center showing our new design;

FIG. 2 is a rear perspective view of the device support for a power and data center of FIG. 1;

FIG. 3 is a right side elevation of the device support for a power and data center of FIG. 1;

FIG. 4 is a left side elevation of the device support for a power and data center of FIG. 1;

FIG. 5 is a front elevation of the device support for a power and data center of FIG. 1;

FIG. 6 is a rear elevation of the device support for a power and data center of FIG. 1;

FIG. 7 is a top plan view of the device support for a power and data center of FIG. 1;

FIG. 8 is a bottom plan view of the device support for a power and data center of FIG. 1;

FIG. 9 is a front perspective view of three of the device supports of FIG. 1, shown positioned along a power and data center; and,

FIG. 10 is a rear perspective view of the device supports and power and data center of FIG. 9.

In the drawings, the broken lines depict unclaimed subject matter only and form no part of the claimed design.
